UNITED STATES PATENT OFFICE.

WARREN W. DUTCHER, OF MILFORD, MASSACHUSETTS.

ROLLER-TEMPLE FOR LOOMS.

Specification of Letters Patent No. 17,559, dated June 16, 1857.

To all whom it may concern:

Be it known that I, WARREN W. DUTCHER, of Milford, in the county of Worcester and State of Massachusetts, have invented an improvement in the Roller-Temple Cases for Looms; and I do hereby declare that the same is fully described and represented in the following specification and the accompanying drawings, of which—

10 Figure 1 exhibits a side elevation of a temple containing my invention; Fig. 2, a transverse and vertical section of it, such being taken through and in line with the axis of its toothed roller; Fig. 3, a transverse section of the roller case showing the recess or space therein to be hereinafter described, the roller not being shown in this figure.

15 In these drawings A, exhibits the toothed roller of the temple, while B, represents the case within which the said roller is situated, and from which projects the bearing or shaft, C, on which the roller is supported and revolves while in operation, such shaft 20 being extended from the end part or head *a*, of the case as shown in the drawings. This case is constructed with a circular or cylindrical recess *b*, formed or sunk within the end part *a*, and of a diameter just sufficient 25 to receive the inner end of the roller and to admit said roller, C, to freely revolve on its shaft. The depth of this recess may be about one tenth of an inch. As it extends entirely around the roller, it serves, during

30 the process of weaving, as a guard to prevent the loose warp or filling threads from getting and gathering between the head or end of the roller and the part, *a*, of the case against which such end revolves. In the common roller temple as ordinarily constructed, without any such recess or guard, the loose warp or filling threads by getting 35 between the roller and head of its case frequently arrest the motion of the roller and thereby cause the cloth to become torn or 40 injured by the points of the roller while the cloth is being drawn forward. Besides this, when a roller becomes so clogged much time and labor are required to be expended 45 in order to remove the obstruction. With 50 my improved case the above mentioned difficulty is not likely to ensue, practice having demonstrated the invention to be one of great practical value in the art of weaving, 55 to which it appertains.

What I claim and desire to secure by Letters Patent, is—

The above described improved roller temple case made with a cylindrical recess for the reception and protection of one head 60 or end of the toothed roller in manner as specified.

In testimony whereof, I have hereunto set my signature.

WARREN W. DUTCHER.
